UNITED STATES PATENT OFFICE.

ARTHUR F. HODGSON, OF JARVIS, ONTARIO, CANADA.

HONEY EXTRACTOR.

Application filed April 5, 1926. Serial No. 99,901.

My invention relates to improvements in honey extractors and more particularly to that type which extracts from both sides of the comb simultaneously, and the object of 5 the invention is to devise an improved type of extractor which will greatly expedite the operation of extracting honey; firstly, by enabling a greater number of combs to be extracted simultaneously in the machine; 10 secondly, by reducing the work and labor involved in loading the combs into and removing them from the extractor; thirdly, by eliminating the necessity for reversal of the combs in the extractor; fourthly, by 15 enabling the standard supers or surplus boxes full of combs to be inserted directly into the extractor for extraction.

A further object is to provide an extractor having extremely large capacity and at the 20 same time keeping the size of the machine within very small and compact limits.

A further object is to enable extraction to be carried out without danger of damaging the comb structure.

25 Other objects will appear in the course of the following specification.

My invention consists essentially of a casing in which is mounted, for rotation about a horizontal axis, a rotor, the rotor being so 30 constructed that comparatively large boxes may be supported therein which boxes are of similar size and shape to the regular supers of the hive and each contains a large number of combs in exactly the same relative arrangement as the combs ordinarily 35 occupy when in the super of the hives; all as hereinafter more particularly described and illustrated in the accompanying drawings in which:—

40 Fig. 1 is a top plan view of an extractor constructed in accordance with my invention.

Fig. 2 is a side elevation thereof.

Fig. 3 is a vertical section on the lines 3—3 of Figs. 1 and 4 looking in the direction of the arrows.

Fig. 4 is a vertical section on the lines 4—4 of Figs. 1, 2 and 3 looking in the direction of the arrows.

Fig. 5 is a side elevation of a rotor used 50 in my invention showing the comb carrying boxes in position therein.

Fig. 6 is a top plan view thereof.

Fig. 7 is a detached fragmentary side elevation of a novel form of a brake used 55 in my invention.

Fig. 8 is a vertical section on the line

8—8 of Fig. 7 looking in the direction of the arrows.

Fig. 9 is a detached perspective view (to a larger scale) of a portion of the frame 60 of the machine and a bell crank lever mounted thereon with the cooperating parts forming the brake operating means.

Fig. 10 is a cross-section (to a larger scale than the other drawings) through one 65 of the comb holding boxes used in my extractor showing the combs therein ready for extraction.

Fig. 11 is a view of the bottom spacer 70 for the combs.

In the drawings, like characters of reference indicate corresponding parts in the various views.

In the form illustrated, my invention comprises a supporting main frame 1 upon 75 which is supported a casing 2.

The upper portion of the casing is hinged at 3 so that the cover portion 4 may be raised to permit access to the interior. This cover portion 4 is shown partly raised in broken 80 lines in Fig. 2.

An outlet 5 leads from the bottom of the casing and provides for withdrawing the extracted honey therefrom.

Within the casing a rotor 6 is mounted 85 upon a horizontal shaft 7 which shaft is journaled in bearing blocks 8 supported upon the main frame 1.

This shaft 7 projects laterally at one side 90 of the casing to accommodate the driving and breaking mechanism as will presently be described.

The rotor 6 is of reel like form and comprises the two side rings 9 and the hubs 10, the rings and hubs being connected by spokes 95

11.

The rotor is rigidly mounted upon the shaft 7 in any suitable manner as by set screws 12.

Angle bars 13 are secured upon the inner 100 sides of the rings 9 and are positioned along the four sides of a square.

These bars 13 thus constitute inwardly directed tracks within the rotor, the purpose of which will presently be explained.

Extending between the rings 9 slightly to the outside of the tracks 13, are transverse bars 14, 15 and 16 and on each bar 14 is slidably mounted a latch 51.

Secured to each angle 13 adjacent to the 110 end thereof remote from the latch 51 is a bracket 17 the arm of which projects in-

wardly of the rotor, to form a stop as will be explained.

Upon the projecting portion of the rotor shaft 7 is rigidly mounted a pulley or wheel 18, the rim of which projects inwardly towards the frame 1.

Upon the outer side face of the pulley 18 is secured a friction disc 19 of wood or other suitable material.

10 A loose pulley 20 is mounted upon a shaft 7 and its inner side face is adapted to bear against the face of the friction disc 19.

Upon the pulley 20 would be mounted the usual belt (not shown) for driving the rotor.

15 Upon the outer end of the shaft 7 is slidably mounted a head 21 and between the head and the hub of the loose pulley 20 is mounted a thrust bearing 22.

The outer end of the head 21 is slotted at 20 23 and through this slot extends a lever 24, a pin 25 connecting the head to the lever.

An arm 26 is secured to the main frame 1 at 27 and the end of the lever 24 is pivotally connected to the outer end of this arm by a pin 28.

The lever 24 extends past the end of the frame 1 and is supported upon an arm 29 projecting laterally outward from the frame 1.

30 A tension spring 30 extends from the lever 24 to the main frame 1 and acts to draw the arm inwardly towards the frame.

A protuberance 31 is formed upon the upper face of the arm 29 the outer end of 35 which is adapted to engage the lever 24 to form a latch or catch for retaining the lever in its outermost position against the action of the spring 30. This will be further explained later.

40 One of the bearing blocks 8 is formed with an upwardly extending arm 32 at the upper end of which is secured a pin 33.

Upon this pin is journalled a disc or plate 34 also carrying an upwardly extending arm 35.

Upon the plate 34 are secured two eccentric pins 36 positioned at diametrically opposite points on either side of the pin 33.

50 Swingably mounted upon the pins 36 are two arcuate brake shoes 37 which form internal and external brake shoes as will presently be explained.

Pivots mounted upon the frame 1 is a bell crank lever 38, the arms of which are indicated by the numerals 39 and 40.

The arm 39 of this bell crank lever is connected to the arm 35 of the plate 34 by a distance rod 41.

60 The arm 40 of the bell crank lever carries a laterally projecting pin 42 and extending between this pin 42 and the main frame 1 is tension spring 43 which normally tends to pull the arm 40 downwardly.

65 A bent pin 44 is rotatably mounted upon the frame 1 and the under face of the arm

40 is formed with a depression 45 into which this pin is adapted to engage as will presently be explained.

Four boxes 46 are used in my machine for mounting the combs 50 in the rotor.

70 These boxes are exactly similar in size and shape to the regular supers used on the hive, which supers as is known are those extra boxes which are placed above the brood chamber of the hive and in which the bees store the surplus honey which is subsequently extracted for sale.

75 The ordinary super is open at top and bottom and the combs are placed therein side by side in spaced apart relation so that the bees enter from the bottom and can freely pass between the combs and over the surfaces thereof to store the honey in the cells.

80 In the extractor boxes 46 the bottom is closed but the top is left open and across the bottom centrally of the length of the box is placed a strip of metal 47 having upwardly bent spaced apart lugs 48 which register with the spaces between the combs so as to maintain the bottom of the combs 85 in their proper spaced apart relation. The tops of the combs are separated by the usual small separators 52 carried by the combs, which separators also separate the combs when in the regular super. This will be 90 clear from an examination of Figs. 10 and 11.

95 Along each side of the boxes 46 are mounted longitudinally extending angle bars 49 the outstanding legs of which form 100 flanges upon the boxes.

The construction and operation of my invention is as follows:—

When the combs 50 have been uncapped they are placed in the boxes 46 each box 105 holding a complete super of combs and when in the boxes 46 they are in side by side, spaced apart relation in exactly the same arrangement as they occupied when in the supers.

110 The lid 4 is raised by any suitable mechanism.

The rotor 6 is turned by hand into a proper position so that one pair of tracks 13 is horizontal and uppermost as in Fig. 3 115 and one of the boxes 46 full of combs is inserted endwise into the rotor.

During this operation the flanges 49 slide upon the tracks 13 and the box is supported upon these tracks. When the box has been 120 fully inserted into its proper position in the rotor the inner end strikes the stop 17 which limits further travel of the box.

When in position the transverse bars 15 and 16 lie just above the box 46 and hold it and the combs 50 therein in position against outward movement due to centrifugal force during rotation of the rotor.

125 The latch 51 is now slid to a central position upon the bar 14 in which position one 130

arm thereof engages the front end of the box 46 and the other arm engages the top of the bar 15. This secures the box positively in position within the rotor and it 5 cannot move in any direction.

By suitably positioning the angle bars 49 upon the boxes, supers of various depths may be accommodated in the rotor. This 10 overcomes certain manufacturing difficulties and enables a machine to operate with all the various depths of combs in use.

The rotor is then turned and the other three boxes 46 inserted in a similar manner, after which the lid 4 is closed and the 15 machine is ready to start extraction.

An examination of the brake mechanism will disclose that the brake is normally applied by the spring 43, which draws the arm 40 of the bell crank lever 38 downwardly so 20 as to draw the arm 35 of the plate 34 towards the left. This turns the plate 34 so as to close the brake shoes 37 towards each other to grip the rim of the pulley 18.

In order to release the brake the arm 39 25 of the bell crank lever is pushed to the right in the direction of the arrow in Fig. 9. This oscillates the plate 34 in a clockwise direction so as to move the brake shoes 37 apart to release the grip upon the rim of the pulley 18.

This raises the arm 40 of the bell crank lever and the brake may be held released by turning the bent pin 44 so that it engages within the depression 45 of the arm 40 and 35 holds this arm raised. As soon as this pin is disengaged the spring 43 again applies the brake.

Extraction is then carried out by rotating the rotor which is driven by a belt through 40 the loose pulley 20.

The brake is released and the drive to the pulley 20 engaged.

The novel arrangement of my drive permits a very flexible and gradual take up 45 when commencing to rotate so that there is no sudden jar upon the rotor and thus there is little chance of damaging the comb structure.

The spring 30 draws the lever 24 inwardly 50 so that the face of the pulley 20 is forced into contact with the face of the friction disc 19 and when the drive is first started and the rotor is at rest, due to the resiliency of the connection between the pulley 20 and disc 19, considerable slip is permitted so that 55 the speed of rotation of the rotor gradually increases and the slip decreases until when the rotor attains its full speed all slip ceases.

This provides an exceptionally efficient 60 and flexible drive which is so necessary in extractors if the frail comb structure is to be retained intact.

In the extraction of honey it is extremely 65 important that the speed of rotation of the rotor increases very gradually at first so

that the bulk of honey is thrown out at this slow speed and when the speed becomes greater the weight of honey remaining in the combs is greatly diminished. If the speed is excessive during the initial period 70 of extraction the violent action of centrifugal force acting upon the great weight of honey in the combs is sufficient to destroy the frail comb structure.

My drive provides this gradual increase 75 in speed rotation of the rotor.

During extraction the combs are positively held in their proper position within the boxes 46 and extraction takes place simultaneously from both sides of the combs. 80

A very important and valuable feature of my invention is that by having the boxes 46 closed at the bottom when in position within the rotor the rush of air upwardly between the combs is eliminated and this together 85 with the action of centrifugal force in rarefying the air inside the boxes, results in extremely thorough extraction and also eliminates all tendency to damage the comb structure. 90

When extraction is complete the drive is disconnected by moving the lever 24 outwardly against the tension of the spring 30 until it engages behind the stop 31 which holds the lever in this outward position. 95 This relieves the pressure between the pulley 20 and friction disc 19 and when the pin 44 is disengaged from the bell crank lever the brakes are applied gradually and resiliently by the spring 43 so that the rotor is brought slowly and evenly to rest with no sudden jar. 100

The boxes 46 may then be removed by sliding the latches 51 to one side and drawing the boxes outwardly after which the combs may be placed directly back in their regular supers ready to be again used upon the hives. 105

It is to be noted, that the disposition of the boxes 46 in the rotor is symmetrical so that the balance of the rotor is perfect. 110

It will be apparent from the foregoing that my machine will be of great value in the commercial extraction of honey in large quantities since it greatly reduces the labor involved. Ordinarily in loading an extractor each comb must be placed in position therein individually and again it must be removed individually whereas in my machine a complete super containing up to twelve combs is inserted into and removed from the extractor as a unit. The saving thus accomplished 115 will be readily apparent. 120

Attention is drawn to the fact that there is no lubrication at any point within the rotor so that there is no possibility of oil contaminating the honey. 125

In my machine the combs are carried in the rotor in four large containers each container accommodating a large number of combs, thus eliminating the necessity for the 130

individual baskets or pockets required in the old type machine.

While I have illustrated and described the use of boxes 46 having permanently closed bottoms, various other methods of closing the bottoms of the boxes when in position within the rotor could readily be provided so that the regular supers which are open at the bottom could be directly inserted into the rotor. This, for instance, might be accomplished either by detachable bottoms for the supers or by a permanent supporting partition within the rotor.

From the foregoing it will be seen that I have devised valuable improvements in honey extractors whereby the objects of my invention have been attained.

Various modifications may be made in my invention without departing from the spirit thereof or the scope of the claims and therefore the exact forms shown are to be taken as illustrative only and not in a limiting sense and I desire that only such limitations shall be placed thereon as are imposed by the prior art or are specifically set forth in the appended claims.

What I claim as my invention is:

1. A rotor for a honey extractor, comprising a reel like member, opposed inwardly directed tracks carried by the sides of the reel, said tracks arranged in opposed pairs and forming the sides of a rectangle at each side of the reel.

2. In a honey extractor, in combination, a casing, a rotor therein rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart, relation, means permitting said boxes to be inserted endwise into said rotor from the circumference thereof and to be supported upon said tracks, and means carried by the rotor for positioning said boxes within the rotor and retaining them with the combs therein in position during rotation of the rotor.

3. In a honey extractor, in combination, a casing, a rotor therein rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart, relation, said boxes adapted to be inserted endwise into said rotor from the circumference thereof and to be supported upon said tracks, stops carried by the rotor positioned to engage the inner end of each box for limiting its travel into the rotor, means car-

ried by the rotor adapted to engage the tops of said boxes when in position within the rotor, and latches adapted to engage the outer end of each box when in its fully inserted position within the rotor.

4. In a honey extractor, in combination, a casing, a rotor therein, rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart, relation, said boxes adapted to be inserted endwise into said rotor from the circumference thereof and to be supported upon said tracks, stops carried by the rotor positioned to engage the inner end of each box for limiting its travel into the rotor, transverse bars carried by the rotor adapted to engage the tops of said boxes when in position within the rotor, and latches adapted to engage the outer end of each box when in its fully inserted position within the rotor.

5. In a honey extractor, in combination, a casing, a rotor therein rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart, relation, said boxes adapted to be inserted endwise into said rotor from the circumference thereof and to be supported upon said tracks, stops carried by the rotor positioned to engage the inner end of each box for limiting its travel into the rotor, transverse bars carried by the rotor adapted to engage the tops of said boxes and also the tops of said combs when in position within the rotor, and latches adapted to engage the outer end of each box when in its fully inserted position within the rotor.

6. In a honey extractor, in combination, a casing, a rotor therein rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart, relation, laterally projecting flanges carried by each box, said boxes adapted to be inserted endwise into said rotor from the circumference thereof so that the aforesaid flanges slide upon the aforesaid tracks to support the boxes within the rotor, stops carried by the rotor positioned to engage the inner end of each box for limiting its travel into the rotor, transverse bars carried by the rotor adapted to engage the tops of the boxes

and combs when in position within the rotor, and latches adapted to engage the outer end of each box when in its fully inserted position within the rotor.

- 5 7. In a honey extractor, in combination, a casing, a rotor therein rotatable about a horizontal axis, said rotor comprising a reel like member, opposed inwardly directed tracks arranged in opposed pairs and forming the sides of a rectangle at each side of the reel, comb holding boxes open at the top and each adapted to accommodate a plurality of combs in side by side, spaced apart relation, laterally projecting flanges carried 10 by each box, said boxes adapted to be insert- ed endwise into said rotor from the circumference thereof so that the aforesaid flanges slide upon the aforesaid tracks to support the boxes within the rotor, stops carried by the rotor positioned to engage the inner end 20 of each box for limiting its travel into the rotor, transverse bars carried by the rotor adapted to engage the tops of the boxes when in position within the rotor, and a latch slidably carried on certain of said 25 transverse bars and adapted to be moved into position thereon to engage the outer end of each box when said boxes are in their fully inserted positions within the rotor.

ARTHUR F. HODGSON.
